UNITED STATES PATENT OFFICE.

CARL H. HAUGK, OF BROOKLYN, NEW YORK, ASSIGNOR OF TWO-THIRDS
TO CARL VOGT AND CHARLES VOGT, BOTH OF SAME PLACE.

CIGAR-BUNCH MOLD.

SPECIFICATION forming part of Letters Patent No. 313,330, dated March 3, 1885.

Application filed September 20, 1884. (No model.)

To all whom it may concern:

Be it known that I, CARL H. HAUGK, of Brooklyn, county of Kings, and State of New York, have invented certain new and useful 5 Improvements in Cigar-Bunch Molds, of which the following is a specification.

This invention has reference to certain improvements in the cigar-bunch mold for which an application for Letters Patent has been filed 10 by me heretofore, Serial No. 134,812, dated June 14, 1884, the invention being designed with a view to cheapen the construction of the mold. The bunch-mold heretofore employed was made of one solid block, into which the 15 head-shaping openings were bored. This required a block of good sound wood, without any cracks, which was connected with some expense.

The object of this invention is to substitute 20 a number of smaller pieces of wood for the solid block, and connect them in a suitable manner; and the invention consists of a cigar-bunch mold made of a series of strips or sections, which are connected by transverse 25 screws and provided with a series of vertical socket-holes that are bored through the block at the meeting edges of the strips.

In the accompanying drawings, Figure 1 represents a perspective view of my improved 30 cigar-bunch mold. Fig. 2 is a plan, and Fig. 3 a vertical transverse section of the same on line *x x*, Fig. 2.

Similar letters of reference indicate corresponding parts.

Referring to the drawings, A A represent a 35 number of strips of wood, that are tightly connected by transverse screw-bolts B, of wood, iron, or other suitable material, that unite the strips into one block. A series of vertical 40 head-shaping socket-holes, *a a*, are bored into the block at the meeting edges of the strips,

said socket-holes being provided at the lower end with narrow openings *b b*, through which the air escapes when the cigar-bunches, enclosed by their wrappers, are inserted into the 45 mold, so as to give the proper shape to the head of the bunches. Molds of this construction can be manufactured cheaper than when the block is made of one solid piece, and offer, furthermore, the advantage that cigar-bunches 50 differing slightly in size can be shaped in the same mold by interposing between the strips forming the mold layers of card-board, by which the size of the holes is increased to some extent, so that a larger size of bunches can be 55 shaped in the mold.

Having thus described my invention, I claim as new and desire to secure by Letters Patent—

In a cigar-bunch mold, one or more longitudinal strips provided on each edge with a 60 series of concave depressions extending downward from the top of the strip and having at their lower ends semi-cylindrical air-outlet grooves, two longitudinal strips having similar depressions and grooves in one face only, 65 adapted to form the outer members of said mold, said depressions and grooves registering with each other when the parts are assembled, and forming cigar-bunch head-shaping apertures with air-outlet openings at their 70 apices, in combination with transverse screw-bolts passing through suitable apertures in the strips for securing the parts in position, substantially as described.

In testimony that I claim the foregoing as my 75 invention I have signed my name in presence of two subscribing witnesses.

CARL H. HAUGK.
